TABLE CONCENTRATOR.

Application filed June 3, 1927. Serial No. 196,367.

This invention relates to novel features in the construction of concentrator decks, and also to a novel form of movement imparted to the deck.

5 Dry table concentrators as usually constructed are provided with a deck having a deck surface that is supported at a transverse inclination and over which riffles extend diagonally to direct the concentrates toward the upper side of the deck.

It is found that the concentrates from which the major portion of the tailings have been removed travel more freely along the channels between the riffles than the unseparated material lying near the material receiving end of the deck. It is therefore feasible to impart a greater transverse inclination to the portion of the deck lying near its discharge end than can be given the portion of 20 the deck lying near the feed hopper.

One important feature of the present invention therefore resides in a concentrator deck having a deck surface that is supported at a transverse inclination and the pitch of 25 which gradually increases from the material receiving end of the deck toward the discharge end thereof. As a result of the gradual change in the inclination of the deck surface, each portion of the deck surface is given 30 the particular transverse inclination that is best suited for the condition of the materials being treated upon that portion of the deck. The increase in the transverse inclination of the deck toward the discharge end thereof 35 also helps to work the tailings out of the concentrates and down the deck surface toward the lower side thereof, and permits the use of steeply inclined riffles.

In the dry concentrator decks as commonly 40 constructed heretofore the transverse inclination of the deck surface employed to promote the flow of the tailings toward the lower side of the deck has been too steep to treat the concentrates lying near the concentrate wall to the best advantage. That is, as the concentrates travel along the concentrate wall 45 they are subjected to a final or high grading treatment, which in many cases can be better performed on a relatively flat surface. Another feature of the present invention therefore resides in a concentrator deck having 50 the marginal portion of the deck surface lying adjacent the concentrate wall disposed at a less transverse inclination than the rest 55 of the deck surface.

Still another feature of the present inven-

tion resides in operating means for a deck whereby an up-throw or vibratory movement is imparted to the deck in a direction to shift the materials slightly toward the material receiving end of the deck, the movement being such that it serves to work the concentrates away from the riffles against which they pile up and tend to overflow.

Other features of the invention and novel combination of parts in addition to the above will be hereinafter described in connection with the accompanying drawings which illustrate good practical forms of the invention.

In the drawings,—

Fig. 1 is a side elevation, with parts in section, of a table concentrator construction in accordance with the present invention;

Fig. 2 is a top plan view of a twin deck such as shown in Fig. 1, the hood extending 75 over the deck being omitted;

Fig. 3 on an enlarged scale is a sectional view taken on the line 3—3 of Fig. 1;

Fig. 4 is a top plan view of the supporting frame for the deck and of means for imparting a vibratory movement to the deck, the deck and its supporting carriage being omitted;

Fig. 5 on an enlarged scale is a sectional view taken on the line 5—5 of Fig. 2, the deck 85 surface being omitted in order to show the construction of the deck frame for supporting the deck surface at a gradually increasing transverse inclination.

Fig. 6 on an enlarged scale is a side view 90 of a portion of the deck supporting frame of Fig. 1;

Fig. 7 is a side elevation of a portion of the deck carriage and shows the supporting arms for imparting an upthrow movement to the 95 deck;

Fig. 8 is a top plan view of a modified type of deck;

Fig. 9 is a sectional view taken on the line 9—9 of Fig. 8;

Fig. 10 is a vertical sectional view through a portion of the deck of Fig. 2 and shows means for removing the concentrates from the deck surface;

Fig. 11 on an enlarged scale is a top plan 105 view of portion of the concentrate wall showing the same provided with different types of deflectors;

Fig. 12 is a side view of the parts shown in Fig. 11;

Fig. 13 is a top plan view of the material receiving end portion of the deck showing

a modified arrangement of the feed hoppers;

Fig. 14 is a transverse sectional view through a twin deck provided with a modified type of riffles, and

Fig. 15 is a sectional perspective view taken on the line 15—15 of Fig. 13.

A number of the features of the present invention may be embodied in a twin deck construction such as shown in Figs. 1, 2, 3 10 and 5; or in a single deck such as shown in Figs. 8 and 9.

Referring first to the twin deck type of concentrator, the same is provided with the 15 oppositely inclined deck surfaces 10 which are supported so that they slope downwardly from the ridge or central portion 11 of the deck surface. The deck frame is preferably so constructed that an air chamber 12 is 20 formed beneath the deck surfaces in order that air may be forced into the air chamber and upwardly through apertures 13 formed throughout the entire deck surface, or any desired portion thereof. The materials to 25 be treated may be fed to the oppositely inclined deck surfaces 10 by the feed hoppers 14 which hoppers, it will be noted, are shown as extending practically entirely across the end of each deck surface to the lower edge 30 thereof, the arrangement being such that the materials will be delivered to substantially the entire end portion of each deck surface by the feed hoppers 14.

As above pointed out, an important feature of the present invention resides in the construction of the deck whereby the transverse inclination of the deck surfaces 10 is gradually increased from the feed end of the deck towards the discharge end thereof. In 40 order to support the deck surfaces in this manner the deck frame is shown as provided with a large number of transversely extending beams 15 which slope upwardly from the opposite sides 16 of the deck frame 45 towards the central ridge 11, and it will be noted from Fig. 5 that the inclination of these beams 15 is gradually increased from adjacent the feed end of the deck towards the discharge end thereof; that is, the beams 50 15 lying near the feed hoppers 14 are shown as having a relatively slight inclination, whereas the beams 15 lying near the discharge end of the deck are shown as having a much steeper inclination. As above indicated a further feature of the invention resides in the construction whereby that portion 55 of the deck surface lying near the concentrate wall is given a flattened construction. This is produced by reducing the inclination of the beams 15 near their inner ends, as clearly indicated by 17 of Fig. 5. By forming the supporting structure for the deck surface in the manner just described the desired transverse inclination may be 60 65 imparted to each portion of the deck sur-

face. The deck surface 10 may be conveniently formed of flexible metal strips 18 that are trough-shaped in cross-section, as shown in Fig. 3 and which have the up-turned side portions adapted to form the riffles 19 as more fully shown in Fig. 7 of my Patent Numbered 1,505,734, granted August 19, 1924. These trough-shaped strips 18 are secured diagonally across the deck surface as shown in Fig. 2, and are sufficiently flexible 75 to readily conform to the gradual increase in inclination of the deck supporting beams 15. The air apertures 13 above mentioned may be formed in the riffle forming channels 18.

As the materials travel lengthwise of the deck the concentrates which work down under the tailings will be directed towards the upper side of the deck by the riffles 19, while the tailings will flow laterally over the riffles towards the lower side of the deck in a well known manner. This separation or stratification of the materials is promoted by the air passing upwardly through the apertures 13 and also by the vibratory movement which is imparted to the deck in a manner to be described. The concentrates upon reaching the ridge or flattened portion 11 of the deck may be caused to travel along a zigzag path such as indicated in Fig. 2 90 near the material receiving end of the deck, or may be otherwise treated to subject them to a final or high-grade treatment. In order to cause the materials to travel over the zigzag path just mentioned, certain of the 95 riffles 19 are extended beyond the other riffles, as indicated by 20, so that they will serve to deflect the concentrates from one side of the ridge 11 to the other, as will be apparent from Fig. 2. This will help to 105 work the remaining tailings out of the concentrates and to direct these tailings down the oppositely inclined deck surfaces 10.

After the concentrates have traveled some distance along the flattened portion 11 of the 110 deck they may be subjected to the action of the deflectors 21 which may be given various different constructions best shown in Figs. 11 and 12. These deflectors may be secured in the desired position of adjustment to the concentrate or upstanding wall 22 extending 115 lengthwise of the deck. The deflectors 21 are inexpensive to construct and may be easily secured to the wall 22 in any desired position lengthwise of the deck by the clamping bolts 120 23. The construction of the deflectors 21 is such that they force the concentrates traveling along the ridge 11 away from the concentrate wall 22 and this serves to crowd the tailings off the flattened surface 11. The deflectors 21 may extend only a short distance from the concentrate wall as shown at the right-hand side of Fig. 11 of the drawing, or if desired these deflectors may be provided adjacent their ends with the raised portion 21' 125 130

adapted to form a skimmer under which the concentrates may pass while the tailings lying above the concentrates will be forced down the inclined sides of the deck. If desired the deflectors 21 may be given the construction shown at the left-hand side of Fig. 12, wherein it will be seen that the scraper 24 is supported by the side plates 25 for vertical adjustment towards and from the deck surface 11 to thereby vary the size of the opening below the scraper 23 under which the concentrates may pass.

It may be desirable to remove the concentrates from the deck surface at different points lengthwise of the deck and this may be conveniently done by providing the openings 26 in the ridge portion 11 of the deck surface, as will be apparent from Fig. 2. Means may be provided for opening and closing the different discharge apertures 26 to thereby regulate the degree of retreatment to which the concentrates are subjected before they are permitted to escape from the deck. While the openings 26 may be formed of various types of gates or closures, one good construction to this end is shown in Fig. 10 wherein it will be seen that each concentrate discharge opening 26 is formed in a plate 27 which may be set in a portion of the deck surface and secured thereto by bolts 28. Each plate 27 may be provided with a downwardly extending lug 29 to which a rocking lever 30 may be pivotally secured by a pin 31. One end of the lever 30 is provided with a head 32 adapted to close the opening 26 and the opposite end of the lever 30 is connected to the rod 33 having a hand operated nut 34 at its upper end and which is adapted to pull the rod upwardly to hold the opposite end 32 of the lever out of its apertured closing position, as will be apparent from the drawing. A spring 35 may be provided to normally hold the lever 30 in its apertured closing position as shown. The air which is confined in the space 12 below the deck surface should be excluded from the discharge openings 26 and the closure means just described. The closure mechanism for each opening 26 is therefore positioned in a chamber formed below the deck surface and from which air under pressure is excluded by the surrounding walls 36, and the concentrates which escape from any one of the openings 26 may fall into a conveyor trough 37 which may be attached to the lower wall 38 of the concentrator deck.

The concentrator deck of Fig. 2 is preferably provided with an upstanding wall 39 at each side thereof and which extends a substantial distance along the lower side of each deck surface 10. These upstanding walls 39 serve to retain a bank of the tailings lying along the lower sides of the deck surfaces 10 upon the deck surface to subject them to a panning action which will cause such concentrates as may remain in these tailings to work down

under the tailings into engagement with the riffles 19 so that they will be directed out from under the mass of tailings towards the concentrate wall. The tailings, upon reaching the end of this wall, may escape from the deck surface into the tailing launders 40, which, in the construction shown, taper in the direction of their length and are arranged to decrease the width of the deck surface toward its discharge end.

The concentrates which reach the discharge end of the flattened portion 11 of the deck may enter a hopper 41 and the middlings which reach the discharge end of the deck may enter the hoppers 42. The concentrates which pass downwardly through the openings 26 into the trough 37 and those which pass through the discharge openings 26 disposed near the discharge end of the deck are directed into the concentrate receiving receptacle 43, as will be apparent from Fig. 1.

As a result of the deck construction so far described it will be seen that as the materials travel lengthwise of the deck the concentrates will travel along the riffles 19 towards the concentrate wall 22 while the tailings which flow over the riffles will work down the inclined deck surfaces towards the retaining walls 39, and as the separation of the materials progresses the transverse inclination of the deck is gradually increased; this will help to crowd the tailings out of the channels between the riffles and to work them towards the lower side of the deck. As a result of this construction each portion of the deck is given a transverse inclination which is best adapted to accommodate the type of materials being treated upon that particular portion of the deck. The transversely inclined riffles 19 are preferably given the tapered construction best shown in Fig. 3 wherein it will be seen that these riffles are taller near the tailing retaining wall 39 than they are near the concentrate wall, this construction being desirable in order that the tailings which tend to stratify above the concentrates may more readily flow over the riffles as they approach the concentrate wall.

As above indicated, a further feature of the present invention resides in deck operating means whereby an upthrow or vibratory movement is imparted to the deck in such a manner that the concentrates are shifted slightly towards the feed hoppers 14 in order to work them away from the riffles over which they tend to flow. While various forms of movements may be employed to produce this desired effect, one good construction to this end will now be described.

In carrying out this feature of the invention movement of the materials lengthwise of the deck towards the discharge end thereof is effected by supporting the deck at a pronounced inclination, as best shown in Fig. 1, wherein it will be seen that the deck support-

ing frame is much taller at the hopper end of the deck than it is at the discharge end thereof, this frame being provided with the relatively short uprights 44 at the right-hand end 5 thereof and the longer uprights 45 at the left-hand end thereof, and to these uprights are secured the longitudinally extending beams 46. In order to accommodate different materials it may be desirable to vary the longitudinal 10 inclination of the deck and to this end in the construction shown the deck supporting frame just described is mounted for rocking movement about the axis of a power shaft 47 to be more fully described. The central 15 portion of the deck supporting frame is supported by a fixed transversely extending beam 48 having the upwardly extending lugs 49 at the upper ends of which are provided saddles or bearing surfaces adapted to receive 20 the outer convexed surfaces of the bearing plates 50, which bearing plates are rigidly secured to the braces 46 of the frame. The arrangement is such that as one end of the deck supporting frame is raised or 25 lowered the entire frame will swing about the axis of the power shaft 47, it being supported for this swinging movement by the bearing brackets 49 the outer concaved surfaces of which are concentric with the axis of the shaft 30 47. When the supporting frame has been tilted to the desired position it may be firmly supported in such position by the use of blocks 51 which are placed between the lower beams 46 and the floor 52 of the building, and the frame may be clamped in this position by the clamping bolts 53 provided at the opposite 35 ends of the concentrator.

One good form of means for vibrating the deck in such a manner that the concentrates will be worked away from the riffles over 40 which they tend to flow consists in supporting the deck so that an upthrow movement is imparted to the same as it is moved back and forth with a vibratory effect, and to this end in the construction shown the deck is supported by the swinging arms 54 the upper ends of which are provided with stub shafts 55 that are journaled in bearing brackets 56 secured to the upper beams 46 of the supporting frame. 45 The lower ends of the arms 54 are provided with the stub shafts 57 which are journaled in bearing brackets 58 secured to the under face of a carriage 59 upon which the deck is mounted.

50 The means shown for imparting a back and forth or vibratory movement to the deck consists of the power shaft 47 above mentioned and which is rotatably mounted in the bearing brackets 60, and this shaft is provided with an eccentric portion 61 upon which a relatively 55 long drum 62 is rotatably mounted, the anti-friction bearing 63 being provided between the drum and the eccentric upon which it is mounted. The deck which is supported 60 for swinging movement in the direction of its

length by the arm 54 is held against moving in the direction in which it slopes by a plurality of cables 64 which are clamped or otherwise secured to the under face of the carriage 59. These cables are looped about the upper 70 grooved sheave 65 rotatably supported by the shaft 66. The cables 64 pass from the sheave 65 about the grooved drum 62 and the ends of these cables extend from the under side of the drum 62 to the springs 67, the arrangement being such that the compressed springs 67 exert a continuous pull upon the cable 64 to hold the deck in approximately the position in which it is shown in Fig. 1. As the eccentric shaft 47 is rotated by its 75 driving pulley 47^a the drum 62 will be moved through an orbital path and this will tend to slack off and tension the cable 64 to impart a slight movement to the deck in the direction of its length. The deck is positively pulled 80 in a right-hand direction viewing Fig. 1 by the power operated cable 68 a portion of which is secured to the carriage 59 by a clamp 69. An intermediate portion of the cable 68 is looped about a grooved sheave 70 supported by the shaft 71 and this cable extends from the under side of the sheave 70 about a groove formed in the drum 62 and the lower end of this cable extending from the drum 62 is anchored to the frame as at 72. As a result 85 of the construction just described, rotation of the eccentric shaft 47 serves to alternately tension and slack off the cables 64 and 68, with the result that the deck is moved back and forth with a vibratory movement, it being 90 understood that as the power cable 68 is tensioned the spring actuated cables 64 are slackened off and vice versa as the cables 64 are tensioned, the cable 68 is slackened off.

In order to impart the desired upthrow 105 movement to the deck the major portion of the arc through which the arms 54 swing lies to the left-hand side of the vertical line *a—a* (see Fig. 7), the arrangement being such that the arms 54 will move back and forth from the 110 position in which they are shown in full lines in Fig. 7, to the position in which they are indicated in dotted lines in this figure. The upthrow movement imparted to the materials by the construction just described will act 115 more energetically on the concentrates lying close to the deck surface than it will upon the tailings which are separated from the deck surface by the concentrates, and as a result the concentrates will be shifted away from the riffles to a greater extent than the tailings. As a result the tailings will flow laterally over the riffles, whereas the tendency of the concentrates to do so will be reduced and the vibratory movement imparted to the deck will 120 tend to spread the concentrates out between the spaced riffles. The operating mechanism just described serves in a very satisfactory manner to prevent the concentrates from 125 escaping over the sides of the riffles provided 130

the movement imparted to the deck is carefully adjusted to produce the desired effect.

The air which is forced upwardly through the apertures 13 in the deck surface may be delivered to the air chamber 12 by a fan 73 which is connected to the air chamber by a pipe 74. A hood 75 is preferably provided over a major portion of the deck surface, as will be apparent from Fig. 1, and air may be exhausted from beneath this hood by a pipe 76 leading to any desired form of exhaust means.

In the modified construction shown in Figs. 8 and 9 a single deck has been illustrated in place of the twin deck above described. In this deck, as in the twin deck, the deck surface 77 is supported at a transverse inclination the pitch of which gradually increases from the material receiving end of the deck towards the discharge end thereof, the deck surface being supported at the desired inclination by a number of transversely extending beams 78 similar to the beams 15 above described. The concentrate wall 79 shown in this modified construction slopes downwardly towards the lower side 80 of the deck, and the concentrate wall is provided with the deflectors 21 which may be similar to those above described. The materials to be treated are supplied to this deck by the hopper 81, and the retaining wall 82 like the retaining wall 39 above described, is provided along the lower side of the deck. This single deck may also be provided with a relatively flat marginal portion 83 which lies adjacent the concentrate wall and upon which the concentrates are subjected to the final or high-grade treatment similar to the action to which they are subjected while resting upon the relatively flat surface 11 above described.

In some cases it may be desirable to feed coarse materials onto one portion of the deck surface and finer materials onto other portions thereof, and means to this end is shown in the modified construction of Fig. 13, wherein the feed hoppers 84 are provided to deliver the materials onto the oppositely inclined deck surfaces 10, and the intermediate hopper 85 is provided to deliver materials onto the ridge portion 11 of the deck. The materials supplied by the hopper 85 may be either coarser or finer than the materials in the hoppers 84, and the coarser materials when delivered to the deck should be subjected to stronger air currents than the finer materials. This may be accomplished by increasing the size of the air apertures 13 provided near the feed hoppers 84, or near the feed hopper 85 as shown in Fig. 15, depending upon which feed hopper contains the coarser materials. The increase in air force may also be produced by forming a separate air chamber under the portion of the deck lying in front of the hopper containing the coarse materials, and the portion of the deck surfaces adjacent the feed hopper 85 is therefore shown as having

the air chamber 86 formed below the deck and into which air under increased pressure may be forced. The increase in air strength of a small area of the deck will serve to quickly stratify the heavier materials after which they may become mixed with the finer materials treated upon the deck and be subjected through the action of the riffles 19 and deflectors 21 to the separating operations above described.

In concentrating certain materials it may be desirable to provide the deck surface 10 with the modified type of riffles shown in Fig. 14 wherein it will be noted that the riffles 87 lean toward the concentrate wall. This arrangement of the riffles causes them to lean or extend over the concentrates traveling along the riffles and helps to prevent the concentrates from escaping therefrom. The leaning type of riffles are particularly desirable in treating ores which contain a small percentage of values, such for example as ores containing free gold in which case the fine particles of gold will accumulate under the leaning riffles and will be prevented by this construction from escaping over the riffles with the tailings.

What is claimed is:—

1. A concentrator deck, comprising a deck frame having a material supporting deck surface, means built into the deck frame for supporting the deck surface at a transverse inclination the pitch of which is gradually increased from the material receiving end of the deck to the material discharge end, and riffles arranged diagonally across the deck surface so that each riffle extends from the lower to the upper side of the deck to direct the concentrates up the transversely inclined deck surface.

2. A concentrator deck, comprising a deck frame having a material supporting deck surface, means for supporting the deck surface at a transverse inclination the pitch of which gradually increases from the material receiving end of the deck toward the discharge end thereof, and riffles extending diagonally across the deck surface from the lower to the upper side of the deck and adapted to direct the concentrates towards the upper side of the deck along paths that are steeper near the discharge end of the deck than they are near the material receiving end of the deck.

3. A concentrator deck, comprising a deck frame provided with a series of downwardly inclined beams arranged transversely of the deck and having their pitch gradually increased from the material receiving end of the deck toward the discharge end thereof, a material supporting surface mounted upon said beams and supported thereby at a transverse inclination the pitch of which increases from one end of the deck toward the other, and riffles extending diagonally across the

deck surface from the lower to the upper side of the deck.

4. A concentrator deck, comprising a deck frame having a deck surface that is supported at a transverse inclination, said deck surface being provided with a marginal portion extending along its upper side and which is disposed at a less transverse inclination to support and retreat the concentrates, riffles extending diagonally over the deck surface to direct the concentrates up the transversely inclined deck surface onto said marginal portion, and deflectors arranged along said marginal portion in spaced relation to the deck surface to arrest the upper but not the lower strata of materials traveling along the marginal portion.

5. A concentrator deck, comprising a deck frame having a deck surface that is supported at a transverse inclination and provided with a relatively flat, marginal portion extending along its upper side and which is disposed at a less transverse inclination to support and retreat the concentrates as they travel lengthwise of said marginal portion, riffles extending diagonally across the deck surface, and deflectors upon said marginal portion and arranged transversely of the riffles to return the lighter materials to the riffles.

30. 6. A concentrator deck, comprising a deck frame having a material supporting deck surface, means for supporting the deck surface at a transverse inclination the pitch of which gradually increases from one end of the deck toward the other, said deck surface being provided with a flattened marginal portion extending along its upper side and which is disposed at a reduced transverse inclination to support and retreat the concentrates, and riffles extending diagonally across the deck to direct the concentrates onto said marginal portion.

45. 7. A concentrator deck, comprising a deck surface that is supported at a transverse inclination, said deck surface being provided with a relatively flat marginal portion extending along the upper side of the deck at a less transverse inclination to receive and retreat the concentrates, and deflectors positioned along said marginal portion in spaced relation to the deck surface so that the values may pass under the deflectors while the lighter materials are directed by the deflectors off of said marginal portion.

50. 8. A concentrator deck, comprising a deck frame having a material supporting deck surface that is supported at a transverse inclination, said deck surface being provided with a relatively flat marginal portion extending along the upper side of the deck at a reduced transverse inclination, riffles extending diagonally over the deck surface to direct the concentrates onto said marginal portion, and deflectors positioned along said marginal

portion and arranged transversely of the riffles to return the tailings that separate out upon said marginal portion to the riffles.

9. A concentrator deck, comprising a deck frame having a material supporting deck surface that is supported at a transverse inclination and the pitch of which gradually increases from the material receiving end of the deck to the material discharge end, a concentrate wall extending along the upper side of the deck, riffles extending diagonally across the deck from the lower to the upper side thereof and arranged to direct the concentrates against said concentrate wall, and a material sustaining wall extending a substantial distance along the lower side of the deck to support a bank of the tailings to subject them to a panning action.

10. A concentrator deck, comprising a deck frame having a material supporting deck surface that is supported at a transverse inclination, a concentrate wall extending along the upper side of the deck, riffles extending diagonally over the deck surface to direct the concentrates against the concentrate wall, deflectors arranged along the concentrate wall to promote retreatment of the concentrates by deflecting the lighter materials back towards the riffles, and adjustable means for securing the deflectors in different positions of adjustment along the concentrate wall.

11. A concentrator deck, comprising a deck frame provided with a pair of oppositely inclined deck surfaces arranged to slope downwardly from a central ridge to form a twin deck construction, the central ridge being formed with an approximately flat surface that extends lengthwise of the deck between the oppositely inclined deck surfaces, riffles extending diagonally over the deck surfaces to direct the concentrates onto said ridge for further treatment, and deflectors arranged along said ridge in spaced relation to the deck surface to clear the values while they engage and deflect the tailings from the ridge.

12. A concentrator deck, comprising a deck frame having a twin deck construction and provided with a large number of beams arranged transversely of the deck to slope downwardly from the opposite sides of a central ridge toward each side of the deck, the beams being arranged so that their pitch gradually increases from the material receiving end of the deck toward the discharge end thereof, a material supporting surface mounted upon the beams at each side of said central ridge and supported by the beams at a transverse inclination that increases in pitch from one end of the deck toward the other, and riffles arranged diagonally across the deck to extend from the lower to the upper side of each deck surface.

13. A concentrator deck, comprising a deck frame provided with a pair of oppositely inclined deck surfaces arranged to slope down-

wardly from a central ridge to form a twin deck construction, riffles extending diagonally over the deck surface to direct the concentrates onto said ridge and having their ends 5 arranged in staggered relation along said ridge to direct the concentrates back and forth in a tortuous path along the ridge.

14. A concentrator deck, comprising a deck frame provided with a pair of oppositely inclined deck surfaces arranged to slope downwardly from a central concentrate wall to form a twin deck construction, riffles extending diagonally over the deck surface to direct the concentrates toward said wall, and outwardly flaring deflector wings secured to the opposite sides of said wall in spaced relation to the deck surface to form skimmers that direct the lighter materials away from said wall for further treatment.
15. A concentrator deck, comprising a deck frame provided with a pair of oppositely inclined deck surfaces arranged to slope downwardly from a central ridge to form a twin deck construction, a pair of feed hoppers positioned to direct the materials onto the oppositely inclined deck surfaces, and a third feed hopper positioned between said pairs of hoppers and adapted to direct a different grade of materials to be treated onto the ridge portion of said deck.
16. A concentrator deck, comprising a deck frame provided with a pair of oppositely in-

clined deck surfaces arranged to slope downwardly from a central ridge to form a twin deck construction, means for forcing air upwardly through the deck surfaces, a pair of feed hoppers positioned to direct the materials onto the oppositely inclined deck surfaces, a third feed hopper positioned between said pair of hoppers and adapted to direct materials to be treated onto the ridge portion of the deck, and means for subjecting the materials delivered to the deck by one of said hoppers to stronger air currents than the materials delivered to the deck by the other 45 hoppers.

17. A concentrator deck, comprising a deck frame having a material supporting deck surface, means built into the deck frame for supporting the deck surface at a transverse inclination the pitch of which gradually increases from the material receiving end of the deck toward the discharge end thereof, and riffles extending diagonally across the deck surface toward the upper side thereof and adapted to direct the concentrates towards the upper side of the deck along paths that are steeper near the discharge end of the deck than the corresponding paths near the material receiving end of the deck. 60

In testimony whereof, I have signed my name to this specification.

ALBERT H. STEBBINS.
